(57) **CLAIM**

I claim the ornamental design for a boat fender apparatus, as shown and described.

DESCRIPTION

FIG. 1 is a front elevational view of the Boat Fender Apparatus showing my new design;

FIG. 2 is a back elevational view of the apparatus thereof;

FIG. 3 is a top elevational view of the apparatus thereof;

FIG. 4 is a bottom elevational view apparatus thereof;

FIG. 5 is a left elevational view of the apparatus thereof; and,

FIG. 6 is a right elevational view of the apparatus thereof.

The stitching depicted by means of roken lines in the figures has been shown for illustrative purposes only and form no part of the claimed design.
